GEORGE W. SWIFT, JR., OF BORDENTOWN, NEW JERSEY.

METHOD OF MAKING OPEN-FACE ENVELOPS.

1,275,323.

Specification of Letters Patent. Patented Aug. 13, 1918.

Application filed April 1, 1915. Serial No. 12,611.

To all whom it may concern:

Be it known that I, GEORGE W. SWIFT, Jr., a citizen of the United States, residing at Bordentown, in the State of New Jersey, have invented a certain new and useful Improvement in Methods of Making Open-Face Envelops, whereof the following is a specification, reference being had to the accompanying drawing.

10 My invention relates to envelopes of the class wherein the openings in the face thereof, for display of the address, etc., are covered by transparent or translucent material sealed thereon to prevent access to the 15 contents of the envelopes through said openings.

In accordance with my method individual envelop blanks, cut from plane paper or other suitable fabric, and of any desired 20 configuration, and respectively provided with openings as aforesaid, and with adhesive material at the margins of said openings, are fed singly, in succession, to mechanism whereby a web of the transparent or 25 translucent material of such length that it may be used to form a plurality, of covers, for successive envelopes, is progressed with its plane normal to the plane in which the envelop blanks are being progressed, and 30 patches of said transparent or translucent material, each of such dimensions as to form a cover for a single envelop opening, are cut from said continuous web, turned parallel with the face of the respective envelop 35 blank provided with the adhesive, and pressed thereon in position to cover the opening therein. 90

I do not herein claim broadly the method of forming transparent coverings for open 40 face envelopes by cutting a succession of patches from a continuous web. Such mechanism has heretofore been used in conjunction with mechanism for progressing a continuous web from which envelop blanks 45 are to be subsequently formed; the latter web being progressed in definite relation to punching mechanism by which openings are formed in it in definite relation to the operation of the patch forming mechanism; the 50 product of such a method being a continuous web having openings covered with patches, which web must subsequently be cut to form individual envelop blanks around the respective openings in the web. 55 Such a method and means for effecting it

are disadvantageous in that but one size of envelopes can be economically made therewith, because, as the envelop web is continuous from the punching to the patching mechanism the openings must be 60 formed therein in invariable relation to the patching mechanism and, if it is desired to form smaller envelopes than those for which the mechanism is designed, it is, of course, necessary to form the blanks for the same 65 respectively surrounding the openings in the web and waste more or less of the web intermediate of said openings. Therefore, my method is advantageous in that envelopes of different sizes may be formed with 70 the same punching and patching mechanism, without waste of material, because it is only necessary to vary the rate at which the separate individual envelop blanks, used by my method, are supplied to the patching 75 mechanism, without changing the rate of operation of the latter. That is to say, in accordance with my method, with the patching mechanism operating at a given rate, small envelop blanks are supplied 80 thereto at a slower rate than large envelop blanks, so as to afford such space between successive envelop blanks as to present the openings therein to the patching mechanism at the proper time; the openings in 85 successive envelop blanks being thus presented in greater spaced relation with each other than in the web from which they were formed without waste of material intermediate of their respective openings. 90

My invention includes the various novel features hereinafter more definitely specified and claimed.

In the drawing; Figure I is a diagrammatic vertical sectional view of mechanism 95 for feeding, cutting and applying the transparent or translucent material to the envelop blanks, and contemporaneously feeding the latter.

Fig. II is an inside face view of a plane 100 envelop blank provided with an opening having adhesive at the margin thereof and adapted to be treated in accordance with my method by the mechanism shown in Fig. I. 105

Fig. III is an inner face view of said envelop blank shown in Fig. II, after the opening therein is covered by a patch of the transparent fabric, by the mechanism shown in Fig. I. 110

Fig. IV is a front view of the completed envelop formed by folding the blank shown in Fig. III.

Fig. V is a rear view of the envelop shown in Fig. IV.

Fig. VI is an inside face view, similar to Fig. II, but showing a different configuration of envelop blank provided with an opening having adhesive at the margin 10 thereof and adapted to be treated in accordance with my method by the mechanism shown in Fig. I.

Fig. VII is an inner face view of said envelop blank shown in Fig. VI, after the 15 opening therein is covered by a patch of the transparent fabric, by the mechanism shown in Fig. I.

Fig. VIII is a front view of the completed envelop formed by folding the blank 20 shown in Fig. VII.

Fig. IX is a rear view of the envelop shown in Fig. VIII.

Referring to Fig. I; the web 1, of transparent or translucent paper or other suitable fabric, is drawn over the guide roll 2 and by the feed rolls 3 and 4 which are so related as to eliminate the curl of said web, due to its having been previously tightly wound. Said feed rolls 3 and 4 present said 25 web 1 in plane form between the shear rolls 6 and 7 which respectively carry cutters 8 and 9 in such co-operative relation as to shear from said web 1 successive patches 10; one such patch being sheared from said 30 web 1 at each revolution of the rolls 6 and 7 in the direction of the arrows indicated in Fig. I. Said mechanism also includes the feed roll 12 which is opposed to said roll 7, and rotated in the direction of the arrow, so 35 as to engage and feed between said rolls 7 and 12 successive individual envelop blanks 14 which are entirely independent of each other. As shown in Fig. II each of said envelop blanks 14 has an opening 15 formed 40 therein having adhesive 16 at its margin; so that, as said blanks are progressed downwardly between said rolls 7 and 12 the patches 10 are pressed upon the successive 45 blanks in position to cover the respective openings therein as shown in Fig. III. Said 50 blanks 14, when creased on the lines 18 indicated in Figs. II and III, may be folded to form envelops 20 as indicated in Figs. IV and V.

55 In the operation above described; said mechanism being operated at a given rate, it is necessary to supply said envelop blanks 14 thereto at such a rate as to present their respective openings 15 in proper relation 60 with the patches 10, as the latter are turned from a plane normal to said blanks, to a plane parallel with said blanks and are pressed thereon between said rolls 7 and 12; said rate of supply of the blanks 14 to the 65 patching mechanism being different from

the rate required for supplying the blanks 23 shown in Figs. VI and VII; said blanks 23 being not only of an entirely different configuration, but longer than said blanks 14, in the direction of their movement with 70 respect to said patching mechanism. However, said blanks 23 are like the blanks 14 in that they are provided with respective openings 24 having adhesive 25 at the margin thereof similar to the openings 15 with 75 the adhesive margin 16 in said blanks 14, and adapted to be covered by patches 10 of the same size, as indicated in Fig. VII. Said patches 10 are applied to the blanks 23 in precisely the same way as they are applied 80 to the blanks 14, as above described; the only difference being in the rate at which said blanks, 14 and 23, are supplied to the patching mechanism; because of their respectively different lengths. Said blanks 23, 85 when creased on the lines 27 indicated in Figs. VI and VII, may be folded to form envelops 28 as indicated in Figs. VIII and IX.

The patching mechanism above described 90 may be supplied with envelop blanks by hand or by any suitable mechanism; for instance, rolls 29 and 30, indicated in dotted lines in Fig. I, may be used to engage the blanks between them and present them to 95 said patching mechanism at the desired rate.

Although I find it preferable to apply the adhesive to the margins of the openings in the envelops, as above described; of course, it may be applied to the patches 10 in position to engage said margins; the only essential being that there shall be sufficient adhesive material between the envelop blanks and the patches to retain the latter.

I do not desire to limit myself either to 105 the particular forms of the envelop blanks or to the details of construction of the mechanism herein shown, as it is obvious that various modifications may be made therein without departing from the essential features of my invention as defined in the appended claims.

I claim:—

1. The method of making open face envelops, which consists in continuously progressing a web of transparent material, successively cutting from said web at a predetermined rate patches of said material of such dimensions as to form covers for envelop openings, supplying individual envelop blanks having openings therein to said patches successively and independently of said patch cutting mechanism, but in such timed relation to the rate at which the patches are supplied that the distance between the proper position of the openings always remains the same, so that the opening in each blank comes into registry with a patch and is covered thereby, irrespective of the character of the blank 115 120 125 130

2. The method of making open-faced envelopes which consists in continuously progressing a web of transparent material, successively cutting from said web, at a predetermined rate, patches of said material of such dimensions as to form covers for the envelop openings and supplying individual envelop blanks having openings therein to said patches successively in a timed relation determined by the position of the openings, said timed relation being such that the distance between the openings always remains

the same and the opening in each blank comes into registry with a patch and is covered thereby irrespective of the size of the 15 blank.

In testimony whereof, I have hereunto signed my name at Bordentown, New Jersey, this twelfth day of March, 1915.

GEORGE W. SWIFT, JR.
